CONTAINER WITH FLANGE-THREAD
AND COVER

Robert D. Williamson, Montclair, N.J., assignor to American Aluminum Company, Mountainside, N.J., a corporation of New Jersey

Filed May 12, 1960, Ser. No. 28,766
4 Claims. (Cl. 220—39)

This invention relates to sheet metal containers and, more particularly, to those adapted to be closed by screw caps.

Metal containers are widely used for holding, distributing and transporting various kinds of material, including grease. They are normally provided with screw-threaded caps or covers and the edges thereof have screw threads formed to mate with the threaded flanges of such caps or covers. When this is done, the inner surfaces of such containers present a corrugated appearance and interfere with fully removing all of the material therefrom, especially if they contain such material as grease.

In accordance with my invention, containers are provided which present straight and smooth inside wall surfaces from the bottom to the top, at which top a bead is formed at the juncture of the side wall and an outstanding generally annular flange. The flange is slit or notched and formed beyond the bead, which serves as a sealing seat for a screw cover or cap, to helical or helicoidal form for mating with the threads of a closure cap, the resiliency of the flange-thread permitting moderate springing thereof as the cover is tightened, so as to releasably frictionally lock the cover in place.

An object of my invention is to provide a container having the equivalent of a threaded open end, simply and inexpensively formed, so that it may be closed by a threaded cap.

Another object of my invention is to provide a container in which the equivalent of a thread is formed adjacent its open end, while still leaving a straight, smooth inside surface on its sidewall.

A further object of my invention is to provide a container as above described, in which the thread equivalent is disposed outside of a bead lying in a plane normal to the axis of the container, and adapted to provide a sealing seat for the screw cover or cap.

These and other objects and advantages will become apparent from the following detailed description when taken with the accompanying drawings. It will be understood that the drawings are for purposes of illustration and do not define the scope or limits of the invention, reference being had for the latter purpose to the appended claims.

In the drawings, wherein like reference characters denote like parts in the several views:

FIGURE 1 is a side elevational view of a container embodying my invention and closed by a screw cap.

FIGURE 2 is an enlarged elevational view of the top or upper portion of the container, as shown in FIGURE 1, after removal of the cap.

FIGURE 3 is an axial sectional view of the upper or open end portion of the container of FIGURE 2, further enlarged, and showing a screw cap in the process of being applied thereon and with which are associated a sealing disc and a gasket.

FIGURE 4 is a view corresponding generally to FIGURE 3, except that the bottom of the container is also fragmentarily shown and in which the cap has been screwed to sealing position.

FIGURE 5 is a view corresponding generally to the upper portion of FIGURE 4 but to a smaller scale and showing a modification.

2

FIGURE 6 is a view corresponding to FIGURE 5, but showing another modification.

FIGURE 7 is a view corresponding to the upper portion of FIGURE 4, but showing still another modification.

FIGURE 8 is a top plan of the cap of FIGURE 3, but to a smaller scale.

FIGURE 9 is a top plan of the container of FIGURE 2, but to the scale of FIGURE 8.

Referring now to the drawings in detail, and first considering the embodiment of my invention illustrated in FIGURES 1 to 4, inclusive, 8 and 9, there is shown a cup-shaped container 11 formed of thin metal, a non-limiting example being aluminum, and which may have the general appearance of a beaker of the type found in chemical laboratories. To that end it has a generally cylindrical wall 12, or one which is circular in section about a central axis and closed at its bottom or at one end by a wall 13. Thus it may be of different shape, such as frusto conical. Although the bottom wall 13 may be flat, it is desirably frusto conical, as indicated at 14, adjacent its line of union with the side wall 12, so as to on stacking fit or nest with the correspondingly-formed or recessed top wall 15 of a screw cap 16 serving as a closure for the container.

The open or top end of the container terminates in an outstanding flange 17. This flange, although generally annular in form, comprises an inner approximately semitoroidal portion 18, desirably lying in a plane normal to the axis of the container 11 and forming a bead on which the cap 16 having a top 15 and a screw threaded skirt 24, or a metal disc 19 with or without an associated gasket 21, may seat. The disc 19 may be made of aluminum or other material suitable to be used as a pressure cushion. This allows for uniform pressure all around the edge to make a tight seal, but provides for the release of pressure if it increases above a selected limit. Thus the space 20 between the edge of the disc 19 and the cap 16 allows for further bending of said disc and release of pressure if needed. The gasket 21, if used, may be made of suitable material such as rubber, cork, paper, foil or the like.

The screw cap 16, although it may have a flat top as indicated at 15' in FIGURE 5, desirably has a top 15 which is concave upwardly, as viewed in FIGURES 3 and 4, or as viewed in FIGURE 6. Although the concavity may be provided by a flat central portion terminating in a frusto conical peripheral portion 22, to nestingly receive the corresponding portions 14 of a container 11 placed therein, as shown in FIGURES 3 and 4, it may be approximately of spherical contour, as indicated at 15' in FIGURE 6.

The flange 17, beyond the bead 18, lies below or toward the bottom 13 of the container 11 from the exterior or sealing surface of said bead. Such outer flange portion 23 is formed with a slit or notch 22' and its portions on either side of said notch are bent in opposite directions, as shown at the right hand of FIGURES 3, 4, 5, 6 and 7, a distance corresponding generally with the pitch of the threads on the skirt 24 of the screw cap to be used therewith. The flange portion 23, from the slit 22' at one end to the other end, is bent to a varying degree, desirably in a die, to provide a flange-thread with a helical or helicoidal surface 25 to engage with the corresponding helical or helicoidal surface 26 of the screw threaded skirt 24 on the cap 16.

While I have described the surface 25 as being helical or helicoidal, it will be understood that it lies at the periphery of a flange, the angularity of which varies from that which extends downwardly and outwardly, as shown in the sectioned portions at the right of FIGURES 3 to 7, inclusive, through a generally horizontal or normal por-

tion, as shown at the left side of said figures, to an upwardly and outwardly extending portion, as shown on the unsectioned part at the right of said figures. The depth of the slit 22 is at least equal to the height of the threads 24 on the cap 16 and is shown slightly greater than that height.

In applying the cap 16, the extreme or lower thread thereof first engages the unsectioned or upper portion of the flange 23 and then gradually engages all along said helicoidal flange, including the horizontal or normal portion and the downwardly sloping portion 25, until the cap is moved from the position of FIGURE 3 to that of FIGURE 4 to press the undersurface thereof against the bead 18 or, as illustrated, the undersurface of the packing gasket 21 against said bead and, if desired, flexing the outer edge portions of said disc 19, and gasket 21 from the position of FIGURE 3 to that of FIGURE 4, thereby resiliently sealing the container 11.

From the foregoing disclosure it will be seen that although it is desirable to accurately form the outer flange portion 23 helically, to match the engaged surface of the threaded skirt 24 of the cap, yet extreme accuracy is unnecessary because of the flexibility of the flange 17 which, upon screwing down the cap 16 thereon, will flex or bend so that the parts of the flange which do not initially accurately mate with the cap threads will be brought to a mating engagement. However, sealing of the container by the flange-thread 23 is not relied on, said flange-thread 23 merely holding the cap 16 on the container 11 and the seal being effected at the bead 18 by the top wall of the cap 16 or a disc or packing associated therewith, as viewed most clearly in FIGURES 4 to 7, inclusive.

In the embodiment of FIGURE 5, the container 11 may be identical with that of the first embodiment, however, the cap 16' is here shown with a flat, rather than a concave, top portion 15', the concavity of the portion 15 of the first embodiment being simulated by a filler member 27, formed of any desired material, which presses on the central portion of a packing gasket 21 and/or disc 19 to, if desired, flex it or them, as shown in FIGURE 4, to securely seal the container 11.

In the embodiment of FIGURE 6, the container 11 is identical with that of the first embodiment but the cap 16'' has its central portion 15'' concave upwardly, that is, convex downwardly, and of generally spherical configuration so as to, upon screwing the cap 16'' into place, press down on the center of the packing 21 and/or the disc 19 and flex it or them, as here shown, to tightly seal the container 11.

In the embodiment of FIGURE 7, the cap 16' is formed like that of FIGURE 3 with a flat top 15' and used therewith is a gasket or washer member 28 which effects sealing by having the bead 18 of the container 11, which corresponds to that of the first embodiment, pressed thereinto, as illustrated, upon screwing the cap in place.

From the foregoing disclosure it will be seen that I have provided a container which may be formed from sheet metal, such as aluminum, steel, brass or the like, by a simple and conventional process, with a bottom 5 formed flat or of other desired shape, and a flange projecting from its upper or open end and connected thereto along a bead which functions as a sealing surface. The flange is generally annular, slit or notched, and on either side of said separation curved to helical form, as in a die, to resiliently mate with the threads on an associated closure cap. In the disclosed construction it is unnecessary that the flange-thread effect the desired seal, as such is accomplished at a bead between said flange-thread and the wall of the container. The container wall, by presenting a smooth inner surface to the contents, facilitates the complete removal of the latter, as well as makes possible a more economical production of the container.

I claim:

1. A sheet metal container comprising a body formed by a side wall generally circular in section about a central axis open at one end and terminating at the other end in a bottom wall, a generally annular resilient flange outstanding from said side wall at the open end thereof, said flange uniting with said wall along an annular bead that presents a convex outer surface disposed in a plane normal to said axis to sealingly engage a closure member, the flange being disposed in a plane approximately perpendicular to said axis and being notched at its edge and displaced axially both ways at opposite sides of the notch and curved helically, and a screw cap including a top and a screw threaded skirt having a screw-threaded connection with the helical edge of said flange to close said open end of the body.

2. A sheet metal container as defined in claim 1 wherein there is a resilient packing disc disposed between the top of said cap and said bead.

3. A sheet metal container as defined in claim 1 wherein the inner side of the top of the cap is convex and engages the central portion of the disc inwardly of the line of contact between the disc and said annular bead to flex the disc and press it into tight sealing contact with said bead.

4. A sheet metal container as defined in claim 1 wherein the top of the cap is flat and with the addition of a filler disposed between said top and said disc inwardly of the line of contact of the disc with said bead to press down on the center of the disc as the cap is screwed to closed position.
